UNITED STATES PATENT OFFICE.

RALPH ADAMS CRAM, OF BOSTON, MASSACHUSETTS, ASSIGNOR TO GEORGE K. BIRGE, OF BUFFALO, NEW YORK.

DESIGN FOR WALL-PAPER.

SPECIFICATION forming part of Design No. 24,897, dated November 12, 1895.

Application filed October 10, 1895. Serial No. 565,292. Term of patent 3½ years.

To all whom it may concern:

Be it known that I, RALPH ADAMS CRAM, a citizen of the United States, residing at Boston, in the county of Suffolk, in the State of Massachusetts, have invented and produced a new and original Design for Wall-Paper, of which the following is a specification, reference being had to the accompanying drawing, showing a part thereof.

10 The design consists of large basket-shaped ornaments connected by ribbons and filled with flowers and leaves, with broad perpendicular stripes or bands on each side of said basket-shaped ornaments and continuous sprays of flowers and leaves between said stripes or bands, as represented in the accompanying drawing.

15 The border of the design is formed of bas-

ket-shaped ornaments filled with flowers and leaves, with bows of ribbon tied to the handles of said baskets and festoons of flowers and leaves connecting said baskets, and broad stripes or bands at the top and bottom of said border, as shown in the drawing.

What I claim is—

1. The design for wall paper herein shown and described.
2. In the design for wall paper the border herein shown and described.

Witness my hand this 5th day of October, 1895.

RALPH ADAMS CRAM.
